UNITED STATES PATENT OFFICE.

RALPH W. SHULTERS, OF BATTLE CREEK, MICHIGAN.

COLLAPSIBLE CONTAINER.

1,345,511.

Specification of Letters Patent.

Patented July 6, 1920.

Application filed February 11, 1920. Serial No. 357,777.

To all whom it may concern:

Be it known that I, RALPH W. SHULTERS, a citizen of the United States, residing at Battle Creek, county of Calhoun, State of Michigan, have invented certain new and useful Improvements in Collapsible Containers, of which the following is a specification.

This invention relates to improvements 10 in collapsible containers.

The main objects of this invention are to provide in a collapsible container an improved discharge regulating means whereby a measured quantity is discharged at each 15 operation.

Further objects, and objects relating to structural details, will definitely appear from the detailed description to follow.

I accomplish the objects of my invention 20 by the devices and means described in the following specification. The invention is clearly defined and pointed out in the claims.

A structure which is a preferred embodiment of my invention is clearly illustrated in the accompanying drawing forming a part of this specification, in which:

Figure I is a plan view of a collapsible container, such as a tooth paste tube, embodying the features of my invention.

Fig. II is a detail view partially in central longitudinal section on a line corresponding to line 2—2 of Fig. I.

Fig. III is a similar detail section with 35 the cap removed.

Fig. IV is a detail section on a line corresponding to line 4—4 of Fig. III, showing structural details.

Fig. V is a top perspective view of the 40 discharge control member.

In the drawing similar reference characters refer to similar parts throughout the several views, and the sectional views are taken looking in the direction of the little 45 arrows at the ends of the section lines.

Referring to the drawing, 1 represents the body of a flexible tube or collapsible container of well known construction provided with a conical discharge end 2 terminating in the threaded neck 3 having the discharge opening 4 therein. The container is provided with a threaded cap 5 which is freely removable.

Within the container, is a disk 6 of a 55 diameter somewhat less than the body of the tube, as shown in Fig. II, the disk being

adapted to seat against the conical portion of the container, as shown in Fig. III. The disk is provided with an arm 7 which extends through the discharge opening 4 to be 60 engaged by the cap 5, so that the disk is forced rearwardly or to its open position when the cap is threaded upon the neck, as shown in Fig. II. The arm 7 is preferably provided with the lug 8 projecting laterally to engage the neck limiting the inward movement of the control disk. This prevents its accidental dislocation before the tube is filled and also prevents its being pushed out of place after the tube is filled. 65 70

In operation, the cap being in position, the disk 6 is held from its seat so that the contents of the tube will flow around the disk into the conical portion of the tube, and when the cap is removed, the pressure 75 of the contents of the container on the disk will force it to its seat, forcing out a charge of the contents, but preventing continued flow thereof.

The arrangement of the arm through the 80 discharge opening keeps this opening free, that is, it prevents the opening from becoming clogged by the dried contents of the tube. With this arrangement of parts, I provide a means for controlling the discharge, whereby a predetermined amount 85 of the tube's contents may be delivered at each operation.

The structure is very simple and economical to produce, and is not likely to become 90 inoperative or get out of repair in use.

Having thus described my invention, what I claim as new and desire to secure by Letters Patent is:

1. The combination of a collapsible container having a conical portion at its discharge end and a threaded neck with a discharge opening in the end thereof, a cap threaded to removably engage said neck, and a disk disposed within said container 95 and adapted to seat on the conical portion thereof, said disk having an arm loosely disposed through said discharge opening to be engaged by said cap and unseated thereby, said arm being provided with a lug at 100 105 its outer end engaging said neck to limit the inward movement of the disk.

2. The combination of a collapsible container having a conical portion at its discharge end and a threaded neck with a discharge opening in the end thereof, a cap threaded to removably engage said neck, 110

- and a disk disposed within said container and adapted to seat on the conical portion thereof, said disk having an arm loosely disposed through said discharge opening to 5 be engaged by said cap and unseated thereby.
3. The combination of a collapsible container having a threaded discharge neck at one end, a removable cap threaded upon 10 said neck, and a discharge control disk disposed within said container for bodily movement longitudinally thereof, said disk constituting a cut-off when in one position and being provided with an arm disposed 15 through the discharge to be engaged by the cap, whereby when the cap is closed the disk is forced to its open position to permit the passage of the container's contents and is carried to its closed position by pressure of 20 the contents of the container thereon when the cap is removed.

4. The combination of a collapsible container having a threaded discharge neck at one end, a removable cap threaded upon said neck, and a discharge control disk disposed within said container for bodily movement longitudinally thereof, said disk constituting a cut-off when in one position and being provided with an arm disposed to be engaged by the cap, whereby when the 30 cap is closed the disk is forced to its open position to permit the passage of the container's contents and is carried to its closed position by pressure of the contents of the container thereon when the cap is removed. 35

In witness whereof, I have hereunto set my hand and seal in the presence of two witnesses.

RALPH W. SHULTERS. [L.S.]
